DESIGN FOR A LOVE SEAT OR SIMILAR ARTICLE

Josef W. Noll, Philadelphia, Pa.

Application March 27, 1946, Serial No. 128,009

Term of patent 7 years

(Cl. D15—8)

To all whom it may concern:

Be it known that I, Josef W. Noll, a citizen of the United States, residing in Philadelphia, Philadelphia County, Pennsylvania, have invented a new, original, and ornamental Design for a Love Seat or Similar Article, of which the following is a specification, reference being had to the accompanying drawing, forming a part thereof, in which:

Fig. 1 is a front perspective view of a love seat or similar article showing my new design;

Fig. 2 is a rear perspective view;

Fig. 3 is a top plan view;

Fig. 4 is a front elevational view; and

Fig. 5 is an end elevational view thereof.

I claim:

The ornamental design for a love seat or similar article, as shown.

JOSEF W. NOLL.
